UNITED STATES PATENT OFFICE.

RICHARD O. BOLT, OF ST. LOUIS, MISSOURI.

DESIGN FOR A BADGE.

No. 37,536.

Specification for Design.

Patented Sept. 12, 1905.

Application filed July 17, 1905. Serial No. 270,143. Term of patent 7 years.

To all whom it may concern:

Be it known that I, RICHARD O. BOLT, a citizen of the United States, residing in the city of St. Louis, in the State of Missouri, have invented a new, original, and ornamental Design for Badges.

The accompanying drawing, which is a front face view, illustrates my new, original, and ornamental design for badges.

I claim—

The ornamental design for a badge as shown.

RICHARD O. BOLT.

In presence of—

ROBT. L. McLARAN,
LENA E. BAER.
